FLOOR-LAYING TOOL

William A. Miller, near Weston, Colo.

Application April 21, 1949, Serial No. 88,755

1 Claim. (Cl. 254—15)

1

This invention relates to tools and facilities advantageously employable in the fitting and laying of flooring boards, and more particularly to means for positively interfitting and holding in place successive elements of tongue-and-groove flooring during the laying thereof over and against a sub-floor, and has as an object to provide an improved flooring clamp characterized by convenience and facility of use.

A further object of the invention is to provide an improved construction and operative interrelation of elements constituting a flooring clamp employable in engagement with a sub-floor to facilitate the laying of matched flooring thereover.

A further object of the invention is to provide an improved flooring clamp susceptible of rapid and convenient operative positioning and manipulation.

A further object of the invention is to provide an improved flooring clamp retentive of pressure-imposing operative adjustment upon release from applied manipulative factors.

A further object of the invention is to provide an improved flooring clamp that is simple and inexpensive of manufacture in rugged, durable form, positive and efficient in operation, and effectively applicable to a wide range of particular uses.

With the foregoing and other objects in view, my invention consists in the construction, arrangement, and combination of elements herein-after set forth, pointed out in my claim, and illustrated by the accompanying drawing, in which—

Figure 1 is a somewhat diagrammatic, perspective view of a preferred embodiment of the invention as positioned and arranged for practical use. Figure 2 is a vertical section, on an enlarged scale, taken through the improvement on substantially the indicated line 2—2 of Figure 1. Figure 3 is a bottom plan view of the construction according to Figure 2, certain elements of the latter view being broken away to conserve space. Figure 4 is a fragmentary, detail section taken substantially on the indicated line 4—4 of Figure 2.

It is wide-spread, conventional practice to construct buildings of many types and sizes with board sub-floors fixed in diagonal or perpendicular traversing relation to the usual floor joists and to subsequently complete the desired finish floor by means of matched boards, generally edge tongued and grooved, laid over and secured to the sub-floor. A factor of consequence in the development of high quality finish floors is the close,

2

intimate edge matching of adjacent boards for the elimination of open cracks and seams, and practical control of said factor is aggravated by irregularities and inequalities inevitably characterizing the boards to be matched as a consequence of warping, twisting, and inaccurate milling, hence pointing the desirability of means employable during the laying of the finish floor to pressure-urge and clamp together the edges of the successively-laid boards as the same are positioned upon and nailed to the sub-floor, and the instant invention is directed to the provision of a conveniently-employable facility of such character.

15 The improvement, as shown, is a unitary assembly of elements associated with and carried by an integral, relatively heavy, arched base 10, preferably formed of metal by moulding or casting, in such size, proportions, and particular contour as may be deemed suitable to its purposes. The base 10 is laterally traversed by an upwardly-arched intermediate portion conveniently opening through the base sides and interrupting the base lower surface to define spaced legs terminating in coplanar surfaces adapted for engagement with a sub-floor, or other supporting area, to dispose the base arch portion as a crown thereabove. The arch leg disposed adjacent the work being done terminates in a relatively narrow surface or face 11 from which integral, pointed lugs or spikes 12 project for anchoring penetration into the sub-floor boards on which the base is placed, while the other of the arch legs terminates in a relatively wider surface or face 13, coplanar with the area 11, from which lugs or spikes 12 project in the same manner and for the same purpose served by the like elements on the area 11. The greater width of the surface 13 is determinative of a flange 14 along and extending laterally from the adjacent arch leg in position to serve as a tread plate whereto pressure may be applied, as by means of an operator's foot, for urging the lugs or spikes 12 of the surface 13 into penetrating engagement with the boards of a sub-floor 15 against which the terminal surfaces of the arch legs are disposed. It is the function of the lugs or spikes 12 to resist the effect of pressures tending to displace the base 10 relative to the supporting sub-floor 15 in a direction perpendicular to the base arch axis with the flange 14 as a leading element, and realization of such function is facilitated by forming the lugs or spikes 12 with faces perpendicular to their respective surfaces 11 and 13 definitive of planes paralleling the arch axis on the

lug or spike sides directed toward the free margin of the flange 14 and tapering the other lug or spike faces to intersect said plane faces in penetrating points.

Spaced webs 16 fixedly or integrally depend perpendicular to the arch axis centrally and interiorly of the base 10 arched portion to terminate in spaced relation with the plane common to the surfaces 11 and 13 and provide a mounting for a hinge pin 17 bridging therebetween parallel to the arch axis and in spaced relation within the arch crown. A slot opens through a portion of the base arched portion and leg terminating in the surface 11 perpendicular to the arch axis and in registration with the space between the webs 16 to operatively accommodate a rigid lever 18 hingedly engaged adjacent one of its ends with the pin 17 and extending thence through said slot to a projection exteriorly of and beyond the base arched portion where it terminates in a manipulating handle. The end of the lever 18 within the arch of the base 10 is spaced from the plane common to the surfaces 11 and 13 and hingedly engages with one end of a rigid link 19 disposed to reciprocate in a plane adjacent and approximately parallel to that of said surfaces 11 and 13 through the end of said slot adjacent the surface 11, and the end of said link exterior to the base 10 fixedly mounts a pressure block 20 whereof the margin remote from the lever 18 is arranged in parallelism with the base 10 arch axis and is longitudinally grooved for conforming engagement with and against the tongued margin or edge of conventional finish flooring boards. One side, or exterior corner, of the base slot portion traversed by the lever 18 is toothed or notched, as at 21, for latching coaction with a detent 22, preferably of ratchet type, operatively associated with said lever and selectively manipulatable thereon through conventional lever-mounted facilities in a usual manner, said detent cooperating with the base slot toothed or notched margin in an obvious relationship effective to releasably latch the lever 18 in positions determinative of various projections of the link 19 and block 20 relative to the base 10.

In the practical use of the improvement, the base 10 is placed upon and pressed into penetrating engagement of its lugs or spikes 12 with the boards of a sub-floor 15 in the manner shown in Figure 1, the free, grooved margin of the block 20 being presented to and parallel with the tongue edge of the flooring board 23 to be acted upon and the base 10 being so spaced from the edge of said board as to provide an effective range of link 19 and block 20 travel outwardly and away from said base through the agency of the lever 18. With the elements so positioned and disposed, pressure applied to move the exterior end

of the unlatched lever 18 relative to the base 10 and toward the flange 14 is transmitted with enhanced leverage through the link 19 and block 20 to crowd the engaged flooring board 23 into intimate marginal engagement with the previously-laid board, in which relation the so-clamped board may be held while being nailed in place through engagement of the detent 22 with the toothed or notched slot margin 21, thus freeing the operator's hands for nailing purposes.

Since changes, variations, and modifications in the form, construction, and arrangement of the elements shown and described may be had without departing from the spirit of my invention, I wish to be understood as being limited solely by the scope of the appended claim, rather than by any details of the illustrative showing and foregoing description.

I claim as my invention:

20 In a tool of the character and for the purposes described, an integral, upwardly-arched base unit of considerable mass open at its ends, a relatively-wider and a relatively-narrower, flat, floor-engaging face terminating the respective 25 arch legs in a common plane parallel to the arch axis and extending the full length of the arch, integral penetrating points projecting perpendicularly from said faces, a tread surface opposed to said wider face and merging into said arch for 30 the application of pressure to effect seating of said wider face penetrating points, a slot aperture formed through the arch crown midlength perpendicular to the arch axis and extending through the arch leg terminating in the relatively-narrower face to an end spacedly-adjacent 35 said latter face, integral webs depending interiorly of said arch on opposite sides of said slot aperture to mount a hinge pin parallel to the arch axis, a lever mounted on said hinge pin for oscillation through said slot aperture and terminating in a handle above the arch, ratchet teeth formed in one side of the slot aperture, a detent on said lever in latching cooperation with said teeth, a projection of said lever below the hinge pin interiorly of the arch, a link hinged to the end of 40 said lever projection to slide through the slot aperture in bearing engagement with the end of the latter adjacent the relatively-narrower face, and a pressure block on the free end of said 45 link exteriorly of the arch.
